Barry E. Negrin

(57) **CLAIM**

The ornamental design for a toy ball catcher, as shown and described.

DESCRIPTION

FIG. 1 is a perspective view of a toy ball catcher, showing my new design.

FIG. 2 is a left elevational view of the toy ball catcher of FIG. 1.

FIG. 3 is a right elevational view of the toy ball catcher of FIG. 1.

FIG. 4 is a rear elevational view of the toy ball catcher of FIG. 1.

FIG. 5 is a front elevational view of the toy ball catcher of FIG. 1.

FIG. 6 is a top elevational view of the toy ball catcher of FIG. 1; and,

FIG. 7 is a bottom elevational view of the toy ball catcher of FIG. 1.

The portions of the drawings that are shown in dashed lines are environmental elements and are not part of the claimed design.

1 Claim, 7 Drawing Sheets

FIG. 1

FIG. 2

FIG. 3

FIG. 4

FIG. 5

FIG. 6

FIG. 7
